US0D1098901S

(12) **United States Design Patent** (10) **Patent No.:** **US D1,098,901 S**
(45) **Date of Patent:** **** Oct. 21, 2025**

(54) **CLIP**

(71) Applicant: **Stor-Med Pty Ltd.**, Orange (AU)

(72) Inventor: **Lloyd Scott**, Orange (AU)

(73) Assignee: **Stor-Med Pty Ltd.**, Orange (AU)

(**) Term: **15 Years**

(21) Appl. No.: **29/932,037**

(22) Filed: **Mar. 11, 2024**

(51) LOC (15) Cl. **09-06**

(52) U.S. Cl.

USPC **D8/356**; D24/128

(58) **Field of Classification Search**
